UNITED STATES PATENT OFFICE

ABRAHAM PODEL, OF NEW YORK, N. Y., ASSIGNOR TO ANCHOR CAP & CLOSURE CORPORATION, OF NEW YORK, N. Y., A CORPORATION OF NEW YORK

SEALED PACKAGE

Application filed May 16, 1927. Serial No. 191,613.

The present invention relates generally to the art of sealing and more particularly to a sealed package.

It is customary in sealing certain products such as ketchup, chili-sauce, and the like, to use two types of closures on each container. One of these is for the purpose of forming a hermetic seal and the other for providing a cover for the container after the hermetic seal is removed and to improve the looks of the package. This auxiliary cap may be telescoped over and secured to the neck of the container below the upper closure in any suitable manner. Ordinary corks have been used to form the hermetic seal but these are difficult to remove and are sometimes forced into the container, which causes considerable trouble. Closure caps commonly known as the Crown cork caps have also been used. These require a special container finish and in addition there is likelihood of chipping the container in removing the cap, thereby getting broken glass into the contents. Further, the seal itself is objectionable due to the fact that it has an edge seal secured in position by metal-to-glass contact with the lower part of the skirt of the cap. These and the other seals which have been attempted are not satisfactory.

The present invention overcomes these difficulties by providing a hermetic side seal on a bottle or the like having the usual commercial finish. The closure is locked to the container through the intermediation of a ring gasket which holds the metal out of contact with the glass and facilitates removal of the closure. The closure itself is inexpensive and is deformed to reduce its external dimension to a minimum so that a second cover may be attached to the container without material difference in the size thereof.

An object of the present invention is to provide an effective, inexpensive side seal on the side wall of a container.

Another object of the invention is to effect a hermetic side seal with a minimum external dimension to facilitate the application of a second closure to the container.

Another object of the invention is to form

an effective side seal on a narrow sealing zone at the mouth of a bottle or the like.

A further object of the invention is to form a side seal on the narrow sealing zone of a bottle by locking the cap thereon through the intermediation of a gasket.

Other and further objects of the invention will be obvious upon an understanding of the illustrative embodiment about to be described; and various advantages not referred to herein will occur to one skilled in the art upon employment of the invention in practice.

A preferred embodiment has been chosen for purposes of illustration and description and is shown in the accompanying drawings, wherein

Fig. 1 is an elevational view of a container and closure prior to the sealing operation, with the closure thereon shown in section;

Fig. 2 is a sectional view, the container being shown in elevation, illustrating one form of sealing operation;

Fig. 3 is a sectional view of an upper closure hermetically sealed to the container and another closure telescoped thereabout and attached to the neck of the container;

Fig. 4 is a view similar to Fig. 3 with the outer closure shown threaded to the neck of the container;

Fig. 5 is an enlarged view of a portion of the cap showing the change in contour during the sealing operation.

Described generally the present invention attains the objects enumerated herein by providing a closure cap having a depending skirt with a bead formed therein adapted to support a gasket. The caps may be applied to the containers by automatic machines and likewise sealed by automatic machines. The bead in the cap has its outer side wall pressed upwardly and inwardly to form a narrow,

deep groove between its upper edge and the skirt of the cap. This permits the diameter of the cap to be materially reduced and the gasket to be effectively restricted about the side wall of the container without deforming the outer side wall of the bead. The lower edge of the gasket is supported so that it is effectively locked against the shoulder below

the sealing zone of a container having the usual commercial finish. A second closure, which may be an ordinary deep drawn screw cap or a deep drawn snap cap, can be telescoped about the upper hermetically sealed cap and attached to the neck of the container.

Referring more particularly to the drawings, there is shown a container 1, here illustrated as a bottle having a narrow annular sealing zone 2 adjacent the mouth thereof. Beneath the sealing zone there is an annular groove 4 which forms with the sealing zone a shoulder 3. A substantially cylindrical zone 5 may extend from the groove 4 to the body of the container where a shoulder 6 may be formed to engage the lower edge of the skirt of the cap. The zone 5 is slightly larger than the sealing zone 2 to co-operate with a cap having a skirt sufficiently large to be telescoped over the cap on the smaller sealing zone.

A closure cap 7 is provided for forming a hermetic seal on the sealing zone 2. This cap preferably comprises a cover portion 8 extending over the mouth of the receptacle, a downwardly depending skirt 9 flared to permit stacking and having an annular bead 10 for supporting a gasket 11. The cap and gasket are placed upon the containers in assembled state and the gasket is supported adjacent the sealing zone 2.

Any suitable mechanism may be utilized for effecting the necessary seal. A preferred form is illustrated in the drawings wherein a die 14 extends over the cover portion of the cap to hold it firmly in position. The external dimensions of the die are slightly less than the external dimensions of the cap, and the outer edge of the die is beveled as shown at 23 to permit the formation of a groove in the upper wall of the bead. A roller or spinning die 15 actuated by any suitable means, (not shown) engages the outer periphery of the bead to spin it inwardly and to effect the seal. The relative shapes of the roller and die are such that the outer side wall of the bead is spun upwardly and inwardly as shown in Fig. 2, when the roller 15 is moved from the dotted line to the full line position. An inturned flange 16 supports the lower portion of the gasket and locks it against the shoulder formed at the lower edge of the sealing zone. The spinning upwardly of the outer side wall of the bead forms a narrow annular groove 17 in the upper side wall which greatly facilitates the reduction of the diameter of the cap and at the same time the lower surface of the groove rests upon the rounded edge of the bottle and prevents the gasket from being pressed therebetween. The inturned flange is sufficiently long to support the gasket firmly against the shoulder and at the same time permits the engagement of a cap opener for the removal of the cap. The gasket is, therefore, prevented

from riding over the upper edge of the receptacle and is held against the shoulder 3 to lock the cap in position without necessitating a metal-to-glass contact.

The outer diameter of the cap 7 permits the application of a second cap 18 as shown in Fig. 3. This cap may engage the lower zone 5 in any suitable manner as by the projections 19 in the skirt of the cap in Fig. 3 or by the threads 20 and 21 on the container and cap respectively in Fig. 4. In either case the second cap may be applied or removed repeatedly if desired.

The upper cap 7 when applied to the container forms an effective hermetic seal which preserves the contents of the container so that it may be kept for a long period of time. When sold to the consumer the cap 18 is removed and a suitable opener applied to the cap 7 for removing it. Thereafter the cap 18 is used as a cover and for partially sealing the container until the contents are used.

It will be seen that a very effective seal has been provided which may be applied to the narrow sealing zone adjacent the mouth of a bottle. The sealing operation is such that the cap is locked to the annular shoulder on the container through the intermediation of the gasket. This not only prevents accidental removal of the cap but likewise increases the effectiveness of the seal. The external dimension of the sealing cap is reduced during the sealing operation sufficiently to permit the application of a second cap having a minimum difference in size. The seal is formed on the outer side wall of the receptacle and does not, therefore, contaminate the edge of the receptacle. Further, the seal is not affected by irregularities on the upper edge of the container. The caps may be readily applied and sealed by automatic machinery and the packages are fully capable of withstanding the rough handling to which they may be subjected in transportation.

While the present invention has been described with particular reference to the formation of a seal at the upper edge of a bottle it is to be understood that many of the features are applicable to sealing generally. It is desired therefore, that the above description be taken as illustrative and not in a limiting sense as various other changes may be made without departing from the spirit of the invention.

Having thus described my invention, I claim:

1. A sealed package comprising a container having a sealing zone in the form of an annular bead or ledge adjacent its mouth in combination with a closure cap, a gasket in the skirt thereof, an annular band of metal spun inwardly to constrict said gasket under and against said ledge, said band of metal being substantially parallel with the side wall of the container throughout its height.

with a narrow flange at the bottom thereof to hold the gasket in place against said ledge.

2. A sealed package comprising a container having a plurality of cap-engaging zones, the upper zone being smaller in size than the lower zone, in combination with a closure cap on the upper zone having a bead in the skirt thereof, a gasket in said bead, said bead being constricted to compress said gasket against said container to form a side seal and to materially decrease the maximum diameter of the closure cap, whereby a second closure cap with a minimum difference in size may be telescoped over said first cap and attached to the lower zone.

3. A sealed package comprising a container having an upper and lower zone for the attachment of closure caps said upper zone being narrow, in combination with a closure cap adapted to fit on said upper zone having a bead in the skirt thereof, and a gasket in said bead, the outer band of metal forming the side wall of said bead being pressed upwardly and inwardly without material deformation of its contour to compress said gasket against the lower portion of the sealing zone of said container and to reduce the external dimension of said cap.

4. A sealed package comprising a container having a narrow sealing zone adjacent the mouth thereof for the attachment of a closure cap thereto and a second sealing zone substantially larger than said upper sealing zone to facilitate attachment of a cover cap thereto, in combination with a closure cap on the upper zone having a depending skirt with a bead therein, and a sealing gasket of vulcanized rubber in said bead, said bead having a deep narrow groove in the upper side wall thereof to permit the band of metal forming the outer side wall to be pressed inwardly substantially to constrict said gasket about the mouth of said container and to decrease the external dimension of the closure cap.

5. A sealed package comprising a container having an annular ledge adjacent the mouth thereof for the attachment of a closure thereto and a substantially cylindrical portion below said ledge adapted to receive a second closure, in combination with a closure cap having a gasket in the skirt thereof, said skirt being deformed to constrict said gasket under and about said ledge substantially to envelop same to form a side seal and a second cap telescoped over said cylindrical portion.

6. A sealed package comprising a container having an annular ledge disposed slightly below the upper rim of the receptacle, said ledge having a narrow vertical sealing zone, a closure cap having a bead in the skirt thereof adapted to be telescoped about the upper end of said container with the bead adjacent the vertical sealing sur-

face on the container, the side of said bead being spun inwardly and upwardly to reduce the outer dimension of the cap and to press the gasket firmly against the sealing surface, the lower edge of the cap being turned inwardly slightly to support the bottom of the gasket and to press it into the groove below the annular sealing surface, said container having a second sealing zone slightly larger than said first sealing zone, and a closure cap mounted on said second sealing zone.

7. A sealed package comprising a container having a narrow annular sealing zone adjacent its mouth and an annular groove beneath the sealing zone in combination with a closure cap having a bead in the skirt thereof, and a gasket in said bead, said bead being constricted inwardly a substantial amount throughout the width of the bead with an inturned flange at the lower edge thereof to support the gasket and to press a portion of said gasket against and beneath the shoulder formed by said groove.

8. A sealed package comprising a container having a sealing zone adjacent the mouth thereof and a second sealing zone of greater diameter than the first said zone, in combination with a closure cap having a bead in the skirt thereof, and a gasket in said bead, said bead being constricted inwardly to decrease the maximum diametrical dimension of the cap, and a second cap telescoped over said closure cap adapted to engage said second sealing zone.

9. A sealed package comprising a container having a sealing zone for the attachment of a closure cap, in combination with a closure cap adapted to fit on said zone having a bead in the skirt thereof, and a gasket in said bead, the outer band of metal forming the side wall of said bead being pressed upwardly and inwardly without material deformation of its contour to compress said gasket against the lower portion of the sealing zone of said container and to reduce the external dimension of said cap.
